W. E. VAN DORN

STEEL END FOR GONDOLA CARS

Filed March 9, 1921

INVENTOR.

W. E. Van Dorn

BY
Chamberlain, Brendenreid
ATTORNEYS.

UNITED STATES PATENT OFFICE.

WILLIAM E. VAN DORN, OF CHICAGO, ILLINOIS.

STEEL END FOR GONDOLA CARS.

Application filed March 9, 1921. Serial No. 450,994.

To all whom it may concern:

Be it known that I, WILLIAM E. VAN DORN, a citizen of the United States, residing at Chicago, county of Cook, State of Illinois, have invented a certain new and useful Improvement in Steel Ends for Gondola Cars, and declare the following to be a full, clear, and exact description of the same, such as will enable others skilled in the art to which it pertains to make and use the same, reference being had to the accompanying drawings, which form a part of this specification.

My invention has for its primary object to produce a steel end for gondola cars which shall be simple in construction, capable of being easily applied, and which shall possess great strength and rigidity and have the capacity of reinforcing the sides of the car body.

The various features of novelty whereby my invention is characterized will hereinafter be pointed out with particularity in the claims; but, for a full understanding of my invention and of its object and advantages, reference may be had to the following detailed description taken in connection with the accompanying drawing, wherein:

30 Figure 1 is an end elevation of a gondola car arranged in accordance with my invention, portions of the cap plate and of the reinforcing foot plate being broken away;

35 Fig. 2 is a top plan view of approximately one-half of the completed end, together with a fragment of one of the car sides;

Fig. 3 is a view similar to Fig. 2, the longitudinal protecting plate on the car side and the cap plate for the end being omitted;

40 Fig. 4 is a vertical longitudinal section through the car on line 4—4 of Fig. 1; and

Fig. 5 is a section taken approximately on line 5—5 of Fig. 1.

Referring to the drawing, 1 represents the floor plate and 2, 2 the side walls of the gondola car. The end of the car is made of sheet metal having, in the arrangement shown, flat marginal portions, 3, 3, at the sides thereof, which flat marginal portions 50 establish the normal plane of the sheet. Parts of these flat marginal portions are bent rearwardly, as indicated at 4, to form flanges lying against the outer faces of the car sides, these flanges and the car sides being securely fastened together by means of bolts, 5, or the like. The metal end is cor-

rugated along vertical lines, the corrugations preferably extending throughout the entire height of the end. In the arrangement shown, the corrugations are straight and of uniform depth, their extreme upper ends, as indicated at 6, lying behind or within the normal plane of the sheet while their extreme lower ends, as indicated at 7, lie without or in front of said plane; the longitudinal elements of each corrugation therefore forming a slight angle with said plane. A reinforcing foot plate, 8, extends across the lower ends of said corrugations, being secured thereto and to the floor plate of the car. Consequently each corrugation is in effect a post firmly attached at its base to and rising from the floor plate of the car; not only producing a very strong end but permitting it to resist great pressure without assistance from the car sides. The lower end of the end itself may be attached to the floor plate in any suitable way. In the arrangement shown, the lower marginal portion of the end is flanged outwardly, as indicated at 9, so that a single set of rivets, 10, will serve to fasten the foot plate, the flange 9, and the floor plate together.

The top marginal portion of the end, just beyond the upper ends of the corrugations is bent outwardly to form a flange, 11, which is preferably wide at the middle and decreases gradually in width toward the sides of the car. On this flange and secured thereto is a cap plate, 12, also wider at the middle than at the ends. The cap plate is provided at its extreme ends with rearward extensions, 13, which overlie the upper edges of the car sides and are preferably riveted or otherwise secured to longitudinal protecting plates or elements, 14, lying upon the upper edges of said sides. The cap plate is also provided with a downwardly and rearwardly inclined extension, 15, which rests upon and is secured to the inclined upper ends, 16, of the corrugations, which inclined upper ends are preferably flattened more or less to provide a considerable area of contact between the corrugations and the cap plate. The ends of the part 15 of the cap plate are connected to the extensions, 13, by means of suitable connecting pieces or webs, 17. It will be seen that the horizontal portion of the cap plate lies on the outer side of the normal plane of the sheet of which the metal end is made, while the rearward extension including the elements 13, 15, and

17, lies on the inner side of said plane, giving to the end a T-beam characteristic.

If desired, the outer margin of the cap plate and its extensions, 18, may be flanged 5 downwardly as indicated at 18 to give added rigidity.

While I have illustrated and described with particularity only a single preferred form of my invention, I do not desire to be limited to the exact structural details thus illustrated and described; but intend to cover all forms and arrangements which come within the terms employed in the definitions of my invention constituting the appended claims.

I claim:

1. A sheet metal car end having flat portions lying in a vertical plane establishing the plane of the sheet, together with straight 20 corrugations extending at an angle to said plane from one side of said plane at the upper ends of the corrugations to the other side of said plane at the lower ends of said corrugations.

2. A sheet metal car end having flat portions lying in a vertical plane establishing the plane of said sheet, and straight corrugations extending downwardly from points on the inner side of said plane to 30 points on the outer side of said plane.

3. A sheet metal car end having flat portions lying in a vertical plane establishing the plane of the sheet, and straight parallel corrugations extending downwardly from 25 points on the inner side of said plane near the top of said end to points on the outer side of said plane near the bottom of said end.

4. A sheet metal car end having flat portions lying in a vertical plane establishing 40 the plane of the sheet, and parallel straight upright corrugations of uniform depth extending at an angle to said plane and so arranged that one end of each corrugation lies on one side of said plane while the opposite 45 end lies on the opposite side of said plane.

5. A sheet metal panel having flat portions establishing the normal plane of the sheet, and straight corrugations extending at an angle to said plane and each having one 50 end lying on one side of said plane and the other end lying on the opposite side of said plane.

6. A sheet metal car end having flat portions lying in a vertical plane establishing 55 the plane of the sheet and corrugations having their elements lying in vertical planes, the upper and lower marginal portions of said end being flanged outwardly, and a cap plate overlying the top flange of said end 60 and having a part extending downwardly and secured to the upper ends of said corrugations.

7. A sheet metal car end having flat portions lying in a vertical plane establishing 65 the plane of the sheet and corrugations hav-

ing their elements lying in vertical planes, the upper and lower marginal portions of said end being flanged outwardly, and a transverse foot plate overlying the lower flange and extending upwardly across and secured to the lower ends of said corrugations. 70

8. A sheet metal car end having vertical corrugations whose upper ends lie on the inner side of the sheet and are flattened, and 75 a cap plate resting on the top of said car end and having a portion extending downwardly across and secured to the flattened upper ends of said corrugations.

9. A sheet metal car end having the upper 80 marginal portion bent outwardly in the form of a flange and having approximately vertical corrugations the upper ends of which lie on the inner side of the car end and are flattened so as to lie in a plane making an obtuse angle with said flange, and a cap resting on and secured to said flange, said cap having a downward extension resting upon and secured to said flattened ends of the corrugations. 85

10. In combination, a car floor plate, a sheet metal end arranged above said plate and having its lower end bent outwardly to form a flange resting on said plate, said end having approximately vertical corrugations 90 the lower ends of which project outwardly, a reinforcing plate extending transversely across and secured to the lower ends of said corrugations and having a flange resting upon the aforesaid flange, and means passing through said flanges and said floor plate to secure them together. 95

11. A sheet metal car end having flat portions lying in a vertical plane establishing the plane of the sheet and corrugations having their elements lying in vertical planes, the upper marginal portion of said end being flanged outwardly, and a cap plate overlying the top flange of said end and having a part extending downwardly and secured to 100 the upper ends of said corrugations. 105

12. A sheet metal car end having flat portions lying in a vertical plane establishing the plane of the sheet and corrugations having their elements lying in vertical planes, 110 the upper and lower marginal portions of said end being bent to form flanges extending at right angles to said plane, and a transverse foot plate overlying the lower flanges and extending upwardly across and secured 115 to the lower ends of said corrugations. 120

13. In combination, a car floor plate, a sheet metal end arranged above said plate and having its lower end bent laterally of the plane of the sheet to form a flange resting on said plate, said end having approximately vertical corrugations the lower ends of which project on the same side of the sheet as said flange, a reinforcing plate extending transversely across and secured to 125

the lower ends of said corrugations and having a flange resting upon the aforesaid flange, and means passing through said flanges and said floor plate to secure them together.

14. A sheet metal car end having flat portions establishing the normal plane of the sheet and corrugations extending downwardly from points on the inner side of said plane near the top of said end, the upper marginal portion of said end being bent outwardly into the form of a flange, and a cap plate secured on said flange and bent downwardly and inwardly into engagement with the upper ends of said corrugations.
15. The combination with the side walls of a car, of a sheet metal end extending between said side walls, the upper marginal portion of said end being bent outwardly to form a flange, a cap plate resting upon and secured to said flange, said cap plate having rearward extensions overlying and secured to said side walls, and a part extending downwardly behind said end and connected at its ends to said rearward extensions.

16. The combination with the sides of a car, of a sheet metal end engaged with said sides and having flat portions establishing the normal plane of the sheet, said end having approximately vertical corrugations whose upper ends lie on the inner side of said plane, the top marginal portion of said end being bent outwardly to form a flange, and a cap plate secured upon said flange, said cap plate having at the ends extensions overlying and secured to said sides and having also a part bent downwardly and attached to the upper ends of said corrugations and connected at its ends to said extensions.
17. In combination, a car floor plate, a sheet metal end resting on said plate and secured thereto, said end having approximately upright corrugations terminating in the vicinity of said floor plate, and a reinforcing plate extending across and secured to the lower ends of said corrugations and secured to said floor plate.

In testimony whereof, I sign this specification.

WILLIAM E. VAN DORN.
